(57) **CLAIM**

The ornamental design for a computer with graphical user interface, as shown and described.

DESCRIPTION

FIG. 1: A front view of a computer with graphical user interface; and,

FIG. 2: A front detail view thereof, showing a detail of the computer with graphical user interface enlarged and separate for clarity of illustration.

While the claim is directed to the ornamental appearance of the computer with graphical user interface, the GUI is for an operation to manually adjust various setting values of a camera function such as white balance, exposure correction, program shift, zoom, manual focus and color tone upon photographing by the computer having a camera function. The evenly-spaced broken lines in FIG. 1 show a computer; the unevenly-spaced broken lines in FIG. 2 are used to indicate a detail view of the computer with graphical user interface shown enlarged and separate for clarity of illustration; all broken lines form no part of the claimed design.
